PORTABLE DEFROSTER FOR REFRIGERATORS AND FREEZERS

George Edward Ammerman, Murfreesboro, Tenn.,
assignor to Edwin L. Wiegand Company, Pittsburgh, Pa.

Filed Feb. 12, 1963, Ser. No. 73,526

Term of patent 14 years

(Cl. D67—2)

FIGURE 1 is a perspective view of a portable defroster for refrigerators and freezers showing my new design;

FIGURE 4 is a side elevational view thereof, a portion of the handle being broken away for convenience of illustration.

I claim:

The ornamental design for a portable defroster for refrigerators and freezers, substantially as shown.
